[57] **CLAIM**

The ornamental design for a multi-person participation game, as shown and described.

DESCRIPTION

FIG. 1 is a front elevational view of a multi-person participation game, showing the game sheet, showing my new design;

FIG. 2 is a rear elevational view thereof;

FIG. 3 is a right side elevational view thereof, the left side being identical;

FIG. 4 is a top plan view thereof, the bottom plan being identical; and,

FIG. 5 is a front elevational view of the game pieces, which are removed by game participants for attaching to the game sheet.
